UNITED STATES PATENT OFFICE

IVY B. ROBERTSON, OF CHARLOTTE, NORTH CAROLINA, ASSIGNOR OF ONE-THIRD TO
FLOYD M. GRESHAM, OF CHARLOTTE, NORTH CAROLINA

DOOR OPERATING MECHANISM

Application filed October 22, 1929. Serial No. 401,533.

This invention aims to provide novel means whereby the door of a building of any desired kind may be opened as a person or vehicle approaches the building, the door closing automatically, but opening automatically, also, when it is desired to move an automobile out of the building.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes may be made in the precise embodiment of the invention herein disclosed, within the scope of what is claimed, without departing from the spirit of the invention.

In the accompanying drawings:—

Figure 1 shows in vertical longitudinal section, a device constructed in accordance with the invention, parts being broken away;

Figure 2 is a fragmental longitudinal section;

Figure 3 is a section on the line 3—3 of Figure 1;

Figure 4 is a section on the line 4—4 of Figure 1;

Figure 5 is a vertical section showing a modification;

Figure 6 is a vertical section showing another modification;

Figure 7 is a cross section on the line 7—7 of Figure 6.

Referring to Figures 1, 2, 3, and 4, the drawings show a support, in the form of a building 1 of any desired kind. The building 1 may be a garage or any other type of structure. Vertical shafts 2 are located at the front of the building 1 and are journaled in bearing brackets 3 on the building. The vertical shafts 2 support doors 4. Two doors are shown, but it is obvious that more or less than two doors may be employed. Box-like housings 5 are located to the rear of the shafts 2 and extend between the roof 6 and the floor 7 of the building 1. In the hous-

ings 5 vertical guides 8 are located. Weights 9 slide vertically in the guides 8. The weights 9 are connected to flexible elements 10 passed over guide pulleys 11 and brackets 12 supported in the housings 5. From the pulleys 11, the flexible elements 10 extend in a substantially horizontal direction, forwardly, and are wound around the upper portions of the shafts 2, the ends of the flexible elements 10 being secured at 15 to the shafts.

A frame 16 extends forwardly from the front of the building 1 and is located on the ground. At the forward end of the frame 16 there is a rearwardly and upwardly inclined runway 17. The numeral 18 designates a foldable platform. The platform 18 comprises a rear member 19 located within the building 1 in front of the floor 7 and forming a continuation of the floor. At its rear edge, the rear member 19 of the platform 18 is pivotally mounted on the frame work of the building, as shown at 20. The forward portion of the rear member 19 of the platform 18 is pivotally connected at 21 to the rear portion 75 of the front member 22 of the foldable platform 18. Rollers 23 are mounted on the forward portion of the forward member 22 of the foldable platform 18, and ride an inclined track 24 carried by the frame 16, or supported in any desired manner, adjacent to the runway 17, the front member 22 of the platform 18 preferably extending downwardly beneath the runway 17 a little way, as shown in Figure 1 of the drawings.

The lower ends of flexible elements 25 are secured at 26 to the side portions of the member 19 of the platform 18, and are located near the pivotal joint 21 between the parts 19 and 22 of the platform. The flexible elements 25 extend upwardly and forwardly around guide pulleys 27 mounted on the brackets 12. The flexible elements 25 are wound at 28 around the upper portions of the shafts 2, the flexible elements being secured at 29 to the shafts. The flexible elements 25 are wound in one direction, at 28, around the shafts 2, and the flexible elements 10 are wound in an opposite direction, at 14, around the shafts 2.

In practical operation, when an automobile

is to be driven into the building, the automobile moves over the runway 17, upon the front member 22 of the platform 18. The said member 22 moves downwardly, and the rollers 23 move downwardly and forwardly on the inclined tracks 24. The rear member 19 of the platform is swung downwardly, the flexible elements 25 are unwound from the shafts 2, the shafts 2 are rotated, and the doors are opened.

When the doors 4 are opened, the flexible elements 10 are wound on the shafts 2, the weights 9 being raised in the guides 8.

The automobile ultimately runs off the rear member 19 of the platform 18 on the floor 7, and then the weights 9 react to unwind the flexible elements 10 from the shafts 2, the doors 4 being closed, and the platform 18 being elevated into the position shown in Figure 1, by the operation of the flexible elements 25.

When it is desired to back the automobile out of the garage, the automobile is first run on the part 19 of the platform 18, the flexible elements 25 rotating the shafts 2 and opening the doors 4. The doors 4 are held open while the automobile is on the front member 22 of the platform 18, but when the automobile runs out off the front member 22 of the platform, the doors will be closed by the weights 9 in a way which will be understood readily by those skilled in the art.

Although the device has been shown and described as connected with a garage, it will be obvious that it can be used with a dog house, barn, dwelling, or any other structure for which it is adapted.

In Figure 5 of the drawings, parts hereinbefore described have been designated by numerals previously used, with the suffix "a".

The modification consists in having the flexible elements 10a and 25a in the form of sprocket chains.

In Figures 6 and 7, parts hereinbefore described have been designated by numerals previously used, with the suffix "b".

Slide rods 30 are mounted for vertical right line reciprocation in guides 31 on the building 1b. Spiral gears 32 are secured to the upper ends of the slide rods 30. The gears 32 mesh with pinions 33 on the shafts 2b that carry the doors 4b. On the lower ends of the slide rods 30 there are horizontal fingers 34 having movement in slots 35 and in brackets 36 mounted on the rear members 19b of the foldable platform 18b. There are abutments 37 on the slide rods 30. Compression springs 38 are disposed about the slide rods 30. The upper ends of the compression springs 38 engage the abutments 37, and the lower ends of the springs bear on the lowermost guides 31.

When either of the platform members 19b or 22b are pressed downwardly by the weight of an automobile, person, or any other object, the slide rods 30 are carried downwardly,

and the gears 32 operate with the pinions 33 to rotate the shafts 2b and to open the doors 4b.

When the weight is removed from the platform member 19b or from the platform member 22b, the slide rods 30 move upwardly under the impulse of the springs 38, the gears 32 cooperating with the pinions 33 to close the doors.

What is claimed is:

1. In a device of the class described, a building having a doorway, a vertical shaft journaled on the building adjacent to the doorway, a door carried by the shaft, a box-like housing mounted on the building to the rear of the shaft, vertical guides located within the housing, a substantially horizontal bracket supported within the housing, pulleys within the housing and mounted on the ends of the bracket, a weight located within the housing and slidable in the guides, a flexible element wound in one direction about the shaft above the door and located in the housing, the flexible element extending in a substantially horizontal direction over one pulley and downward to connection with the weight, a platform supported below the door for vertical movement, a second flexible element wound in an opposite direction about the shaft above the door and located in the housing, the second flexible element extending in a substantially horizontal direction over the other pulley and downwardly to connection with the platform.

2. In a device of the class described, a building having a doorway, a vertical shaft journaled on the building adjacent to the doorway, a door carried by the shaft, a box-like housing mounted on the building to the rear of the shaft, a flexible element wound in one direction about the shaft above the door and located in the housing, the flexible element extending in a substantially horizontal direction from the shaft, and thence downwardly within the housing, a second flexible element wound in an opposite direction about the shaft above the door and located in the housing, the second flexible element extending in a substantially horizontal direction from the shaft, and thence downwardly within the housing, a platform supported below the door for vertical movement, the second flexible element being connected to the platform, means located within the housing for guiding each of the flexible elements intermediate their ends, and means located within the housing for applying tension to the first-specified flexible element.

3. In a device of the class described, a building having a doorway, a vertical shaft journaled in the building adjacent to the doorway, a door carried by the shaft, a platform mounted for vertical movement below the door, flexible elements wound in opposite directions around the shaft above the door,

one flexible element being connected to the platform, means for applying tension to the other flexible element, pulleys guiding the flexible elements intermediate their ends, and spaced apart, and an elongated bracket on which the pulleys are mounted, the bracket being carried by the building and being inclined downwardly toward the door, thereby to dispose the pulleys at different heights and to keep the wound portions of the flexible elements vertically separated on the shaft.

4. In a device of the class described, a platform comprising rear and front members disposed at an angle to each other and having their inner ends pivotally connected together, means for pivotally mounting the outer end of the rear member of the platform to enable the platform to have vertical movement, a fixed track having a downwardly inclined forward edge, a roller journaled on the outer portion of the front member of the platform and movable downwardly along the inclined edge of the track as the platform moves downwardly and flattens, a vertical shaft supported for rotation, a door carried by the shaft and located above the platform, means operatively connected to the shaft and to the platform for rotating the shaft and opening the door when the platform is depressed, and means for closing the door.

In testimony that I claim the foregoing as my own, I have hereto affixed my signature.

IVY B. ROBERTSON.
